(57) **CLAIM**

The ornamental design for a tablet wall dock, as shown and described.

DESCRIPTION

FIG. 1 shows a right isometric view of a first embodiment of a tablet wall dock in a closed position.

FIG. 2 shows a left isometric view of the first embodiment of the tablet wall dock in the closed position.

FIG. 3 shows a front elevational view of the first embodiment of the tablet wall dock in the closed position.

FIG. 4 shows a front elevational view of the first embodiment of the tablet wall dock in the closed position and in a vertical orientation.

FIG. 5 shows a top plan view of the first embodiment of the tablet wall dock in the closed position.

FIG. 6 shows a bottom plan view of the first embodiment of the tablet wall dock in the closed position.

FIG. 7 shows a left elevational view of the first embodiment of the tablet wall dock in the closed position.

FIG. 8 shows a right elevational view of the first embodiment of the tablet wall dock in the closed position.

FIG. 9 shows a right isometric view of the first embodiment of the tablet wall dock in an open position.

FIG. 10 shows a left isometric view of the first embodiment of the tablet wall dock in the open position.

FIG. 11 shows a top plan view of the first embodiment of the tablet wall dock in the open position.

FIG. 12 shows a bottom plan view of the first embodiment of the tablet wall dock in the open position.

FIG. 13 shows a left elevational view of the first embodiment of the tablet wall dock in the open position.

FIG. 14 shows a right elevational view of the first embodiment of the tablet wall dock in the open position.

FIG. 15 shows a left isometric view of a second embodiment of the tablet wall dock in the closed position.

FIG. 16 shows a right isometric view of the second embodiment of the tablet wall dock in the closed position.

FIG. 17 shows a front elevational view of the second embodiment of the tablet wall dock in the closed position.

FIG. 18 shows a top plan view of the second embodiment of the tablet wall dock in the closed position.

FIG. 19 shows a bottom plan view of the second embodiment of the tablet wall dock in the closed position.

FIG. 20 shows a left elevational view of the second embodiment of the tablet wall dock in the closed position.

FIG. 21 shows a right elevational view of the second embodiment of the tablet wall dock in the closed position.

FIG. 22 shows a left isometric view of the second embodiment of the tablet wall dock in the open position.

FIG. 23 shows a right isometric view of the second embodiment of the tablet wall dock in the open position.

FIG. 24 shows a top plan view of the second embodiment of the tablet wall dock in the open position.

FIG. 25 shows a bottom plan view of the second embodiment of the tablet wall dock in the open position.

FIG. 26 shows a left elevational view of the second embodiment of the tablet wall dock in the open position; and,

FIG. 27 shows a right elevational view of the second embodiment of the tablet wall dock in the open position.
